UNITED STATES PATENT OFFICE.

ROBERT A. WOOLDRIDGE AND GEORGE W. FRASURE, OF EAST LYNNE, MO.

DOOR-THRESHOLD AND WEATHER-STRIP.

SPECIFICATION forming part of Letters Patent No. 362,693, dated May 10, 1887.

Application filed October 22, 1886. Serial No. 216,938. (No model.)

To all whom it may concern:

Be it known that we, ROBERT A. WOOLDRIDGE and GEORGE W. FRASURE, natural born citizens of the United States, residing at 5 East Lynne, in the county of Cass and State of Missouri, have invented certain new and useful Improvements in Door-Thresholds and Weather-Strips; and we do hereby declare the following to be a full, clear, and exact description of the invention, such as will enable others skilled in the art to which it appertains to make and use the same.

This invention relates to improvements in metallic or rubber weather - strips for the thresholds of doors of dwelling-houses and other structures, and has for its object the prevention of the passage of water under the doors during rain-storms or from other causes.

To this end the invention consists in the 15 novel construction and arrangement of parts, as will be hereinafter more particularly described and specifically claimed.

In the accompanying drawings, to which reference is made, and which fully illustrate 25 our invention, Figure 1 shows a door open and the weather-strip covering the channel in the threshold. Fig. 2 shows the door closed and the weather-strip raised to prevent passage of water thereunder. Fig. 3 is a detached 30 view of the weather-strip, and Fig. 4 is a sectional view.

A represents the frame-work of a doorway, constructed in the usual manner, the inner sides being provided with the strips or cleats 35 a, extending from the top to the bottom, against which the door B, hung upon hinges b, closes.

C is a wooden or metallic sill or threshold, having a narrow channel or groove, c, cut 40 longitudinally therein, within which is fitted a right-angled metallic, rubber, or other suitable weather-strip, D, having pintles d at each end, and loosely pivoted or resting in recesses d', formed in the ends of the groove or channel at each side of the doorway, said strip having also a vertical projection or trip, E, upon its upper side at one end, and against which a downwardly-projecting plate, E', secured upon the lower left-hand corner of the 45 door B, strikes in closing the door, which

trips and automatically operates the weather-strip D. The corner of the door is slightly rabbeted or cut away at a right angle to allow the trip to pass and meet the plate E'. The weather - strip lies normally flush with the 55 sill or threshold when the door is open, as the door striking against it turns it down to cover the channel and rises to cover the space below the door and between it and the threshold when the door is closed. Intersecting laterally with the groove or channel in the threshold are a series of orifices, F, which carry off or convey outside all water which may have accumulated in the groove. The weather-strip D, when closed against the inside of the door, forms a perfect protection from rain for the inside of the dwelling, while when in its normal position—that is, when the door is open—it lies so flat or flush with the sill as to preclude any possibility of a 60 person tripping over it when passing through the doorway. An opening or hollow, e, in the sill is provided to receive the trip E when the door is closed and the plate E' forces the trip down.

In the foregoing description it will be obvious that the construction of our device is simple and its operation effective and expeditious.

Having thus fully described our invention, 75 what we claim therein as new, and desire to secure by Letters Patent, is—

1. The combination, with the door having a lower corner rabbeted or cut away at a right angle, said corner being covered by a metallic 80 plate secured to the door, whereby the trip is prevented from cutting into the wood of said door and at the same time rendered operative, of the plate E', a sill having a longitudinal channel, c, provided at its ends with recesses 85 d' d', a right-angled weather-strip, D, having its pintles d d resting in recesses at the ends of the channel, and said trip engaging with the metallic door-plate, substantially as described.

2. In combination with the sill and threshold C, provided with the longitudinal channel c, having end recesses, d' d', and the lateral discharge-openings F, the weather - strip D, having the trip E, engaging with a metallic 90

plate covering a right-angled rabbet in the lower edge of the door, said weather-strip being provided with the pintles *d d*, resting in the recesses of the sill, and the door *B*, rabbeded 5 at one of its lower corners to allow the trip to pass and engage with the metallic plate *E'*, all substantially as and for the purposes described.

In testimony whereof we affix our signatures in presence of two witnesses.

ROBT. A. WOOLDRIDGE.
GEORGE W. FRASURE.
